ACCESSORY FOR STEERING

John Lester Barr, Chevy Chase, Md.

Application May 5, 1934, Serial No. 724,168
Renewed October 13, 1936

19 Claims. (Cl. 280—150)

My invention relates to mechanisms which facilitate the steering of vehicles in circumstances such as parking and unparking vehicles in confined spaces.

5 It is particularly adapted to facilitate steering of automotive vehicles. It is an object of the invention to provide a pressure operated lift element capable of elongation while at the same time permitting the element to be moved into a position out of the way of the operating mechanism of the car and without materially affecting the road clearance thereof.

10 A further object of the invention is to provide a mechanism of the type described which tends to center itself transversely and longitudinally.

15 Another object of the invention is to provide a lift element capable of elongation which is so constructed as to give a substantially uniform lift per unit of elongation regardless of the transverse displacement of its ground engaging portion.

20 Still another object of the invention is to provide a lift element which may move forward or backwards, or sidewise in either direction, without injury to the mechanism, in response to movement of the vehicle while the device is in use.

25 Still another object of the invention is to provide a lift element which will, when it is in use, compensate for any movement of the vehicle without injury to the device or to the vehicle, and which will, by reason of said compensating provisions, operate smoothly.

30 A still further object of the invention is to provide a cam device which, in cooperating with the elongating portion of the lift element, will compensate for lateral displacement of the foot and lift element with respect to a fixed spot on the vehicle.

35 Yet another object of the invention is to provide a lift element which is constructed so that it inherently retains its characteristics of uniform lift even though the vehicle has been moved transversely during the lifting operation.

40 With these and other objects in view, which may be incident to my improvements, the invention consists in the parts and combinations to be hereinafter set forth and claimed, with the understanding that the several necessary elements 45 comprising my invention may be varied in construction, proportions and arrangement, without departing from the spirit and scope of the appended claims.

45 In order to make my invention more clearly understood, I have shown in the accompanying

drawings means for carrying the same into practical effect without limiting the improvements in their useful applications to the particular constructions, which, for the purpose of explanation, have been made the subject of illustration.

5 In the drawings:

Fig. 1 is a view in side elevation partly diagrammatic, showing my lift device in ground engaging position attached to the front axle of the automobile.

10 Fig. 2 is a detailed front elevation of my device showing in dash lines transverse displacement of the lift element and the operation of the device for compensating for such movement, and also in dot dash lines the device raised into the inoperative position.

15 Fig. 3 is a view taken along line 3—3 of Fig. 2, looking in the direction of the arrows.

20 Fig. 4 is a view taken along line 4—4 of Fig. 2, looking in the direction of the arrows.

25 Fig. 5 is a detailed sectional view taken through a longitudinal axis of the fluid pump.

30 Fig. 6 is a view of a modified form of the device, such view being a view in front elevation.

35 Fig. 7 is a sectional view taken along the longitudinal axis of the piston of a modified form shown in Fig. 6.

40 Referring to the drawings, Fig. 1 shows a side frame 1 on which is hung a front spring element 2 by means of a front spring shackle 3 and a rear spring shackle 4. The spring 2 is attached to the axle 5 by means of U-bolts 6. The axle 5 has attached to its front side a support 7 which comprises a U-shaped member having a base 8, a side piece 9 and a front 11. The support 8 is attached by means of U-bolts 12 to the axle 5. The front 11 of the support 7 is in effect a cam plate and is provided with a cam surface 13.

45 I have shown a cylinder head 14 provided with an aperture 15 in its upper end. The cylinder head 14 is tightly fitted around a cylinder 16. The cylinder head is provided with slots 17 in which fit pivot members 18 and 19. The pivot member 19 is inserted in aperture 21 formed in the base 8 of the support 7. The pivot member 19 is provided with a reduced portion 22 which actually fits in one of the slots 17. The other slot 17 fits over a reduced portion 23 of the pivot 18 which is inserted in portion 11 of member 7 and which is provided with a nut 24, a spring holding section 25 and an outer annular disc 26. The construction permits pivoting of the cylinder 16 and the cylinder head 14 on the pivots 18 and 19 and also permits the cylinder head and cylin- 50

der to slide up and down by reason of the slots 17.

In the cylinder is mounted a piston 27 which has a key way 28 which engages with a key 29 carried by a cylinder head 31. The cylinder head 31 fits tightly to the cylinder 16 and is provided with stub shaft extensions 32 and 33. The base plate 8 of the support 7 is provided with cam surface corresponding to the surface 13 of front plate 11 and also surfaces corresponding to the surfaces 34 and 35 of the front plate 11. Mounted on stub shaft 32 is a roller 36 which is adapted to bear against these cam surfaces which correspond to the cam surfaces 13, 34 and 35 formed 15 on the front plate 11 and which can be easily discerned from an inspection of Fig. 2.

Stub shaft 33 is provided with a roller 38 which is adapted to follow over the cam surfaces 13, 34, and 35 formed on front plate 11 of support 7. 20 A holding screw 39 holds this roller 38 in position. The roller 38 can be held in position by reason of the configuration of the base 8.

Mounted on the piston 27 is a fluid-tight head assembly of the usual type which I have designated by numeral 41 in the drawings.

In communication with the aperture 15 and the cylinder head 14 is a fluid-tight fixture 42 communicating with a flexible tube 43 through which is adapted to be fed fluid, such as oil, 30 under pressure to the cylinder to operate the piston.

The piston 27 is provided with an arm 44 having a spring catch 45 on its end. There is formed a bifurcated support 46 at the end of the piston 27. Mounted on the piston 27 is a spring member 47 which is attached to the arm 44. Pivoted in the bifurcated support 46 on a pivot 48 is a female member 49 of a compression element 50. The female member is internally screw threaded 40 and is adapted to receive a screw threaded member 51 provided with a ball 52. The ball 52 fits into sockets in a foot piece 53 and is held in place by holding plate 54 which may be fastened by holding screws 55 to the foot piece 53.

45 A lock nut 56 holds the members 51 and 49 at the proper adjusted length for the compression element. Fastened to a support 57 is a Bowden wire member 58 which passes through a hollow holding nut construction 59 on a support 60 which is held by U-bolts 61 on the axle 5. A spring member 62 is affixed to the support 60 and is adapted to bear against the upper surface 50 of the holding plate 54 of the foot member 53.

Spring 62, in combination with Bowden wire 58 acts as an anti-rattle. Bowden wire 58 passes through a cover sheath 63 and the wire 58 is attached to a ring 64 which may be mounted on a steering post 65 of the car. The ring 64 can be pulled to pull up on the Bowden wire 58 and 60 to pull the mechanism up into the position shown in dotted lines in Fig. 2, at which time Bowden wire 58 holds the mechanism in the up position at the side of the axle and the spring 62 is exerting pressure on the top of the foot member. 65 A suitable hook (not shown) can be provided on the steering post on which the ring 64 can be hooked to hold the device in its up position as shown in dotted lines in Fig. 2.

Mounted on the frame 1 is a support 66 to 70 which is pivoted at 66' a link 67. Link 67 is pivoted at 68 to a hand lever 69. To the hand lever 69 is pivoted at 71 a fastening member 72. Fastening member 72 is attached to piston rod 73.

75 Piston rod 73 passes through a packing gland

74 mounted in a head 75. The head 75 fits within a cylinder 76 which is provided with a breather hole 77 and a filler screw 78 which may be removed to fill the cylinder 76 which acts as a reservoir for the operating fluid, which may be 5 oil.

The head 75 is screwed as indicated at 79 into another head 81. The piston 73 is adapted to reciprocate in aperture 82 in the head 75. A lock nut 83 holds the ensemble together, the cylinder 76 being held between head 81 and fitting over the head 75, the lock nut 83 exerting tension holding the whole together in operative position.

In head 81 is a relatively large valve aperture 15 84. From the aperture 84 is a communicating port 85 which leads to the aperture 82 in the head 75. There is another port 86 that leads into the interior 87 of the cylinder 76. Another port 88 leads into another enlarged valve aperture 89. In the valve aperture 84 is a ball 91 which is held pressed against the port 86 by means of spring 92. A screw head 93 holds the spring 92 in position.

A spring 94 holds the ball 95 in the aperture 25 93 against the port 88. An apertured screw plug 96 bears against one end of the spring 94 and has a passageway therein through which fluid may pass to an enlarged aperture 97 formed in the head 81.

The enlarged aperture 97 communicates with a port 98 that leads into the interior 87 of the cylinder. A conical valve member 99 is adapted to seat in a conical seat provided in the entrance to the port 98. In the top of the head 81 fits a screw threaded member 101 into which is also screwed a nut member 102. Between the two members is packing 103. Both members 101 and 102 are apertured to provide for the passage of a valve stem 104 which carries an operating head 105 at its upper end.

On the head 81 is provided a support 106 upon which is pivoted at 107 an operating lever 108 which is operated by an operating rod 109. The operating rod 109 is adapted to be moved downwardly to pivot lever 108 to raise the head 105 and hence the rod 104, and release the conical valve 99 from its seat, as will be later described.

In operation the lever 69 is operated by hand by the operator to reciprocate the piston 73. Oil is drawn on the back stroke, i. e., to the left with the parts in the position shown in Fig. 5, through port 86 raising the ball 91. The oil then passes through port 85 into the aperture 82 in front of the piston 73. When the piston 73 moves to the right, the oil in front of the piston is forcibly ejected through ports 85 and 88, raising the ball 95 and delivering the oil into valve aperture 97 whence it passes through connection 112 into pipe 111, thence into the flexible tubing 43 from whence it is delivered into the aperture in the cylinder 16 lying above the piston head 41. This oil forces the piston 27 downwardly.

Previously, the ring 64 had been manipulated to operate the Bowden wire 58 to permit the device to occupy its down position. The vehicle, on operation of the pump, as described, will be slightly raised to relieve the weight at least in part on at least one of the steering wheels, permitting them to be turned readily.

In turning the steering wheels, which may be partially contacting the roadway, and operating the mechanism, the device may at times tend to assume the positions indicated by dotted lines in Fig. 2, which occur at the bottom of that figure. 75

The device may more completely assume these positions if during the use thereof, with the steering wheels cramped, the vehicle is permitted to move even slightly by releasing the brake of the vehicle. The foot brake will preferably be used for convenience of operation to hold the vehicle stationary while the device is being used to relieve weight on the steering wheels, and it is readily apparent that the driver's foot may very easily slip or otherwise ease up on the pressure maintained on the foot brake, thus permitting the vehicle to move some, especially when he is using the device on hills.

It is apparent that this device, by having a universal movement, will never be subjected to any strains and the danger of breaking that would occur and exist if it had a possible swinging motion in only one direction, be that direction either longitudinal or lateral. This is due to the fact that in turning the steering wheels while they are contacting the roadway, even though the vehicle is at rest, there is a virtually lateral movement imparted to that end of the vehicle to which they are attached, which, in the conventional motor vehicle, is the front axle. This movement is due to the manner in which the steering wheels are mounted on the conventional motor vehicle.

Because of the contact of the rollers 36 and 38 with the cam surfaces 13, the effective lift per unit of movement of the piston 27 will be approximately the same within certain defined limits.

In operation, the rollers pass over the cam surfaces 13, and the upper slotted portions 17 of the cylinder head 14 slide on the pivots 18 and 19.

It is to be noted that the spring 47 tends to prevent longitudinal displacement of the compression element. There is a spring 113 which exerts a tension between pivot 25 and spring attachment member 45. This spring 113 tends to center the device from lateral or transverse movement. Since the forces exerted by the rollers on the cam surfaces 13 under tension of this spring tend to bring the device into the position shown in solid lines at the bottom of Fig. 2. This spring 113 also performs the function of holding the piston 27 up in the cylinder 16 when the device is not actually being used in lifting, and so in driving the vehicle after one lifting operation of several that are normally required when parking, the compression element is automatically raised from contact with the roadway, as it is so adjusted that when not under pressure from the piston 73, the foot 53 rides a little ways above the roadway in the lowered position.

When it is desired to release the device, the operator presses upon a pedal 114 mounted on the floor board 115 of the car. This pedal 114 is provided with a bell crank lever 116 which is pivoted at 117. The bell crank lever pushes downwardly on the rod 109 and raises the valve 99 from its seat in the port 98, thus permitting the fluid under pressure in the cylinder 16 to pass through the port 98 back into the interior 81 of the cylinder 76. This use of the pedal 114 is all that is necessary after each use of the pump. As the device is left in the vertical position during the entire parking maneuvering operation, spring 113 holds it out of contact with the roadway as the vehicle is moved.

It is contemplated that this device may be mounted on the front axle at a point midway between the two steering wheels, or that it may

be mounted off to one side of the middle point. The side mounting would be the only one adaptable for use on vehicles that have no front axle, the mounting being at some convenient place on the structure, provided in such vehicles, on which provision is made by the manufacturer for jacking up a front wheel. The difference between the central and side positions of mounting is that in the central position, certain movements of the compression element occur which are absent when the mounting is at the side. The reason for this difference is that when the central mounting is used, it is contemplated that there will not be enough lifting length provided in the piston 27 to raise the wheels of the vehicle completely off the roadway, but only enough to relieve the wheels of a sufficient amount of the weight of the vehicle to allow them to be turned readily, leaving the wheels in contact with the roadway.

In the use of the side mounting, where only one wheel is relieved by the lifting device, provision may be made for either partially taking the weight off that wheel, leaving it in contact with the roadway, or there may be provided sufficient lifting length in piston 27 to raise the wheel itself free of the road. In turning the steering wheels, when the mechanism for relieving weight on the wheels is in use, the device may at times tend to assume the positions indicated by the dotted lines in Fig. 2, which occur at the bottom of that figure.

This is due to the fact that in turning the steering wheels while they are contacting the roadway, even though there is no forward or backward motion of the vehicle, there is a virtually lateral movement imparted to that end of the vehicle to which they are attached, which in the conventional motor vehicle is the front end. The reason for this is that the front or steering wheels are mounted on the vehicle in such a manner as to provide for easy steering of the vehicle and long life for the tires, and the same mounting that accomplishes these objects causes the front end of the vehicle to move sidewise when the steering wheels, provided they are contacting the roadway, are turned while the vehicle is at rest.

In the conventional motor vehicle the two steering wheels are mounted on spindles which are mounted on the vehicle, usually one on each end of the front axle, by means of king pins through spindle yokes. In some of the later models of motor cars, the front axle as such, is done away with and there is provided a different construction for the front wheel mounting, but they too have the spindle for each wheel and the king pin for attaching the spindle to the vehicle. It is in the method of mounting the spindle, the king pin, and the spindle arm, that provision is made for easy steering and long tire wear.

Caster, camber, king pin inclination, toe-in, and turning radius are the names given to the different phases of steering wheel mounting, and they are all present in the conventional motor car, as each plays its part, and has its function to perform.

Caster is the name given to the rearward leaning of the king pin to produce a trailing effect to the front wheels. The king pin is tilted backwards at the top by the method of mounting the axle to the front longitudinal car springs, and as it is a straight pin, that means that the bottom end of it is pointing forward of the point on the roadway where the center of the tire is

resting. Just as in the case of any kind of caster, there results the effort of the wheels to run in a straight ahead position, due to their trailing position.

5 When the vehicle turns a corner, caster has the effect of tending to cause the wheels to come back to the straight ahead position. This is because the king pin, being tilted backward, and the wheel turning on the king pin, there is a 10 lift given to the axle at the point where the inside wheel is mounted and a drop or lowering given to the axle at the point where the outside wheel is mounted. After the driver releases the 15 wheels from the turning force which he has applied they will tend to straighten out.

Lest it be confusing how this up and down motion is given to the two ends of the axle, perhaps it is well to cite the fact that the inside wheel, on the turn, really moves backwards, that 20 is, in relation to its point of mounting where the spindle yoke is fastened in by the king pin, and the outside wheel moves forward. Of course, the result is that the king pins being tilted backward, the two wheels move oppositely in relation to the tilt of the king pins. The inside wheel 25 on the turn will cause the portion of the vehicle to which it is attached, usually the axle, to rise, because as the wheel turns backward, the spindle, due to the backward tilt of the king pin, tries to come closer to the ground. Of course, 30 this is impossible as the wheel is around the spindle and will not permit the spindle to get closer to the ground than the radius of the wheel. However, when the spindle comes into 35 the position caused by turning the wheel backwards, something must compensate for this dropping effect, and what happens is that the axle, to which the spindle is attached, rises.

So also, on the other end, the wheel that 40 turns moves forward in relation to the king pin, and due to the backward tilt of the king pin, the spindle, as it swings around, rises. Of course, the wheel cannot rise with the spindle as it must stay on the ground and carry the weight 45 of the vehicle, so what happens is that the axle is drawn closer to the ground at this point. The wheel cannot get closer or farther from the ground as its position on the ground is always the same, but that is not true of the spindle, 50 the angle of which, up and down from the end of the axle, changes, and the axle, or other part of the vehicle to which it is attached, moves up and down in response to these changes.

Now it is apparent that even though the vehicle 55 be at rest, there will be a sidewise motion imparted to the front end of the vehicle if the steering wheels are turned, because of the rearward tilt of the top parts of the two king pins. As the two wheels turn, even though the vehicle 60 is not moving either forward or backward, the front end of the vehicle shifts sidewise opposite to the direction in which the wheels are turned, being impelled in that direction by the same forces which cause the axle at the inside 65 wheel to rise and at the outside wheel to drop, as described above.

Camber is the name given to the angle that the steering wheels are inclined outward at the 70 top. This is accomplished by the angle at which the spindle is mounted to the end of the axle, there being a sloping of the spindle, making the outer end of the spindle come closer to the ground than the inner end. The purpose of this camber is to cause the point of road contact of

the tire to come under the center of the king pin.

The king pin is mounted in such a way that the top of the king pin is inclined in toward the longitudinal axis of the vehicle, and the bottom projects outward along the line of the front axle. 5 This is necessary in the present day motor cars with their small wheels and big tires, if the camber given to the wheels is to be practicable. Without it, there would have to be such a great 10 amount of camber in order to place the road contact portion of the tires under a king pin mounted perpendicularly, that the wheels would have so great an inclination outward at the top that steering of the vehicle on turns would be 15 difficult, side strain on the wheels themselves would be severe, and there would even be danger of forcing a tire off the rim of the wheel. Motions due to camber are cared for by this device. 20

Camber adjustment without toe-in provision would cause the tires to wear on the shoulders. Toe-in is the phrase used to describe the inward inclination of the front portions of the wheels and it is obtained by mounting the spindles so that their outside, or free ends, are a little forward of the axle. This takes the weight off the shoulders and puts it upon the center of the tires, and also produces a marked steadyng effect upon the steering of the vehicle. Toe-in may cause certain motions that must be absorbed by my 30 device, and its construction permits such motions to be absorbed during operation.

There is provision made in the steering assembly of a motor vehicle to take care of the different sized arcs on which the two front wheels 35 travel when the vehicle makes a turn. This is called the turning radius, and it is obtained by setting the spindle arms, which turn the spindles through the spindle yoke around the king pin, obliquely from the steering knuckle. In this way, the wheels must spread apart at the front as they are turned, thus causing the outside wheel to run in a large arc and the inside wheel in a small arc. This construction also imposes certain motions on the front of the vehicle when 40 cramping the wheels.

All of the above indicates the complex factors which affect this device in operation. The various features of construction which it embodies enable it to function smoothly and efficiently and to care for the variables which occur in its use. 45

In Figs. 6 and 7 I have shown an alternate form of the device which comprises a support 200 which is attached by means of U-bolts 201 to the front axle 5. The support 200 is in effect a cylinder head and is provided with an aperture 202 which communicates with the flexible tubing 43. Screwed into the support 200 is a cylinder 203. Adapted to slide in the cylinder 203 is a piston 204 having the usual piston head 205 which I have indicated generally. Another cylinder head 206 is screwed over the cylinder 203. The piston 204 is provided with a bifurcated end 207 which carries a pivot 208 on which is pivoted a support piece 209.

The support piece 209 has a pivot 211 which passes through bifurcated construction 212. The two pivots 211 and 208 comprise a universal joint. The compression element is attached to bifurcated structure 212 and comprises two compression struts 213 set at an angle with a bracing member 214 between them. To the bracing member 214 is attached Bowden wire 58. Each of the compression struts 213 carries a ball 215, which fits within foot pieces 216.

There is provided on the support member 200 a spring support 217. On the piston 204 is another spring support 218. The spring 219 has its ends supported at 217 and 218. Spring 219 tends to compress the device into its collapsed or upper position. The tension of the spring 219 of course acts in addition to the weight of the vehicle which latter quickly forces piston 204 towards its upper position until the feet 216 are ready to leave the roadway, when spring 219 completes the upward movement of cylinder 204.

In the collapsed condition of the device, it may be raised to the horizontal position on pivot 211 as indicated in Fig. 7 in dotted lines. In operation, when feet 216 are on the ground, there may be transverse or lateral displacement of compression struts 213 at any time during the operation, but such lateral or transverse displacement will not greatly change the amount of lift which 20 will be obtained per unit of relative movement between the cylinder 203 and the piston 204. This is apparent from an inspection of Fig. 6. The plurality of compression struts in combination with the feet members cause the members 25 to give substantially uniform lift per unit of elongation (see dotted lines, Fig. 6, which show that this phenomenon occurs). In this form of device there will be greater lift at points between the two positions shown of the lower or longitudinal 30 swung compression elements 212 and 213, but this greater lift will not be harmful in operation of the device.

This device will center itself vertically after each lifting operation, as spring 219 raises piston 204 so that foot pieces 216 are clear of the ground, and the struts 213 will swing freely on pivots 208 and 211 to a vertical position.

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding the scope of the appended claims.

Even when only one of the steering wheels is in contact with the ground, the various motions described herein at least in part occur.

I claim:—

50 1. In a steering accessory, a lift element, a foot member therefor, means to elongate the lift element, and means adapted to give substantially uniform lift regardless of lateral displacement of the foot element.

55 2. In a steering accessory, a lift element, a foot member therefor, means to elongate the lift element, means adapted to give a substantially uniform lift regardless of lateral displacement of the foot element, and means permitting the lift element to be held out of operative position with its longitudinal axis substantially at right angles to that of the vehicle.

3. In a steering accessory, a lift element, a foot member therefor, means to elongate the lift element and cam means cooperating with the lift element to give a substantially uniform lift regardless of the lateral displacement of the foot element.

70 4. In a steering accessory a lift element, means supporting the lift element for universal movement on the vehicle, a foot member therefor, means to elongate the lift element and means to give a substantially uniform lift regardless of lateral displacement of the foot element.

5. In a steering accessory, a lift element, means supporting the lift element for universal movement on the vehicle, means resisting transverse displacement of the lift element, a foot member for the lift element, means to elongate the element and means adapted to give a substantially uniform lift regardless of lateral displacement of the foot element. 5

6. In a steering accessory, a universally pivoted lift element, a foot member therefor, means to elongate the lift element, means tending to prevent transverse displacement thereof, means tending to prevent longitudinal displacement thereof and means adapted to give substantially uniform lift regardless of lateral displacement 10 of the foot member. 15

7. In a steering accessory, a lift element, a foot member therefor, a piston formed thereon, a cylinder in which the piston can reciprocate, a source of fluid under pressure adapted to operate the piston to elongate the element and means adapted to give substantially uniform lift for a given piston movement, regardless of the lateral displacement of the foot member within predetermined limits. 20 25

8. In a steering accessory, a lift element, a foot member therefor, a piston formed thereon, a cylinder in which the piston can reciprocate, a source of fluid under pressure adapted to operate the piston to elongate the element and means 30 adapted to give substantially uniform lift for a given piston movement, regardless of the lateral displacement of the foot member within predetermined limits, and a release mechanism permitting the return of the piston to its initial position. 35

9. In a steering accessory, a lift element, a foot member therefor, a piston formed thereon, a cylinder in which the piston can reciprocate, a source of fluid under pressure adapted to operate the piston to elongate the element, means permitting the element to be held out of operative position with its longitudinal axis substantially at right angles to that of the vehicle and means adapted to give substantially uniform lift for a given piston movement regardless of lateral displacement of the foot member within determined limits. 40 45

10. In a steering accessory, a lift element, a foot member therefor, a piston formed thereon, a cylinder in which the piston can reciprocate, a source of fluid under pressure adapted to operate the piston to elongate the element, cam means cooperating with the element to give substantially uniform lift regardless of lateral displacement of the foot element. 50 55

11. In a steering accessory, a lift element, means supporting the lift element for universal movement on the vehicle, a foot member for the element, a piston formed on the element, a cylinder in which the piston can reciprocate, a source of fluid under pressure adapted to operate the piston, and means adapted to give substantially uniform lift regardless of the lateral displacement of the foot member within determined limits. 60 65

12. In a steering accessory, a lift element, means supporting the element for universal movement on the vehicle, means tending to prevent transverse displacement thereof, a foot member therefor, a piston formed on the element, a cylinder in which the piston can reciprocate, and a source of fluid under pressure adapted to operate the piston to elongate the element. 70

13. In a steering accessory, a lift element, 75

means supporting the element for universal movement on the vehicle, means tending to prevent transverse displacement thereof, a foot member therefor, a piston formed on the element, a cylinder in which the piston can reciprocate, and a source of fluid under pressure adapted to operate the piston to elongate the element, and means adapted to give a substantially uniform lift for a given piston movement 10 regardless of lateral displacement of the foot member within determined limits.

14. In a steering accessory, a lift element, a foot member therefor, a piston formed thereon, a cylinder in which the piston can reciprocate, means supporting the lift element for universal movement on the vehicle, means tending to prevent transverse displacement of the element, means tending to prevent longitudinal displacement of the element, a source of fluid under pressure adapted to operate the piston to elongate the element, and means adapted to give a substantially uniform lift for a given piston movement regardless of lateral displacement of the foot member within determined limits.

15. In a steering accessory, a lift element, means permitting it to be held out of operative position with its longitudinal axis substantially at right angles to that of the vehicle, a foot member therefor, a piston formed thereon, a cylinder in which the piston can reciprocate, a source of fluid under pressure adapted to operate the piston to elongate the element, means adapted to give a substantially uniform lift for a given piston movement regardless of lateral displacement 30 of the foot member within determined limits and a release mechanism permitting return of the piston to its initial position.

16. In a steering accessory, a lift element,

means supporting the lift element for universal movement on the vehicle, a foot member therefor, a piston formed thereon, a cylinder in which the piston can reciprocate, a source of fluid under pressure adapted to operate the piston to 5 elongate the element, means adapted to give a substantially uniform lift for a given piston movement regardless of lateral displacement of the foot member within determined limits and a release mechanism permitting return of the piston 10 to its initial position.

17. In a steering accessory, a lift element, means supporting the lift element for universal movement on the vehicle, cam means cooperating with the element to give a substantially uniform 15 lift regardless of lateral displacement of the element, a foot member therefor, a piston formed thereon, a cylinder in which the piston can reciprocate, and a source of fluid under pressure adapted to operate the piston to elongate the 20 element.

18. In a steering accessory, a lift element adapted to be elongated presenting a relatively broad base, bracing means cooperating with the base to present a lift element substantially the 25 same effective length regardless of transverse displacement, and means supporting the lift element for universal movement on the vehicle and through which it is attached thereto.

19. In a steering accessory, a lift element, 30 adapted to be elongated, a plurality of compression struts therein, and a plurality of pivot feet therefor to cause the lift element to give a substantially uniform lift per unit of elongation even though occupying positions transversely 35 placed from the vertical.

JOHN LESTER BARR.
